UNITED STATES PATENT OFFICE.

RALPH E. LAPHAM, OF OAKLAND, CALIFORNIA.

CENTRIFUGAL SEPARATING MEANS.

Application filed October 1, 1919, Serial No. 327,713. Renewed July 8, 1922. Serial No. 573,633.

To all whom it may concern:

Be it known that I, RALPH E. LAPHAM, a citizen of the United States, residing at Oakland, in the county of Alameda and State of California, have invented certain new and useful Improvements in Centrifugal Separating Means, of which the following is a specification.

This invention comprises certain novel improvements in centrifugal machines of the class designed for separating values of gold, platinum, or the like, from sand, commonly known as black sand, found on beaches and even inland from the seacoast, at many different places in this country.

The invention involves a type of machine quite similar to that presented in my pending application Serial No. 102,533, filed June 8, 1916, which has eventuated into Patent No. 1,336,968, dated April 13, 1920, the machines of said application and my present invention utilizing a centrifugally operating bowl over the inner wall of which a mobile separating medium, preferably mercury, is designed to flow in practice. The pulp or sand and water to be operated on by the machine is supplied to the bowl and caused to travel in contact with the separating medium so that the separating action may be effected. This separating action takes place incident to the movement of the values, which are of greater specific gravity than the separating medium, through said medium, the residual ingredients of the pulp being of comparatively less specific gravity than the separating medium passing off in a properly directed course to a suitable outflow.

The principal features of invention in my present machine reside in certain special means employed to separate the mobile separating medium from the gangue, or overlying substances which travel with and over the surface of the separating medium as the values pass through the latter. Again I utilize novel means for regulating the quantity of mercury or separating medium supplied to the bowl in the operation of the latter.

The foregoing together with other detail features of construction and operation will be fully understood on reference to the description found hereinafter, in conjunction

with the accompanying drawings in which:

Figure 1 is a sectional view of a separating machine embodying the invention.

Figure 2 is an enlarged sectional view of the upper portion of the bowl and bringing out more clearly the means whereby the separating medium becomes separated from the overlying residual portions of the pulp obtained after the separation of the values therefrom.

Figure 3 is a plan view and part sectional view showing primarily the arrangement of the valve plate and the operating means by which it is adjusted.

Figure 4 is a combined fragmentary perspective view showing especially the lever and connected parts of the valve operating means.

Describing the invention specifically, my machine may comprise any suitable base A, with which is combined in any substantial manner a casing B, the latter enclosing the centrifugally operating bowl 1 of the separator. The bowl 1 is supported by an upper shaft 2, fitted solidly into the bowl, as shown at 3, so as to rotate therewith. At its upper end, the shaft 2, is mounted in a bearing structure, shown at 4, and comprised of obvious detail parts. At its lower portion, the bowl 1 is provided with a tubular extension 1^a, in which is screwed the upper end of a lower shaft 5, the lower end of shaft 5 being supported in a bearing structure 6 similar to the structure 4. A pulley support and housing 7 encloses the encased bearing structure 6, and a pulley 8 is mounted on the upper portion of said support, as seen best in Figure 1. The pulley 8 is freely supported by suitable bearings to travel at relatively high speed and a coil or any equivalent spring 9 connects the pulley 8 with the portion 1^a of the bowl 1. The member 9 affords a non-vibratory connection intermediate the pulley 8 and the bowl 1 such that the radial shocks of the belt and power pulsations communicated to the pulley 8 are not transmitted to the shaft 5 or the bowl 1. The spring 9, of course, carries the rotating load but it will be evident that this load is small once the bowl is placed in rotation.

As seen in Figure 1, a chute 10 leads through an opening in the top of the casing

B to a hopper 11 and affords a means of supplying the pulp from which the values are to be separated, to the bowl 1. The pulp received by the hopper 11 passes out of the bottom of the hopper on to a bottom member 12 in the bowl 1, said bottom member being a sort of false bottom for the bowl and substantially quite similar to the corresponding construction shown in my above identified application. Beneath the bottom member 12, the bowl 1 is provided with the reservoir or chamber 13, designed to contain a separating medium such as a mercury. The separating medium is adapted to pass upward over the inner wall 14 of the bowl 1, said wall being the inner surface of a wall member 15, which fits in the bowl 1, is comprised of a ring like body, and is positioned in spaced relation to the outer wall proper of the bowl. The wall member 15 is equipped with the annular grooves or pockets 16, in which the values are intended to be caught during the centrifugal separating operation.

Practically, at the top of the bowl is an annular mercury chamber 17, formed by an overflow rim 18, secured by screws or like fastenings to the upper end of the bowl 1, said rim constituting an overflow rim for the gangue as the latter passes off to the discharge launder 19. The rim 18 has an outward extension 20, which curves downwardly and partially enters the launder 19. The discharge for the launder 19 is designated 21 and is of known construction. The bottom of the mercury chamber 17 is comprised of a ring 22, screwed on to the upper end of the wall member 15 above described. The ring 22 has openings 23 therein, through which the mercury or separating medium may pass to an overflow reservoir 24, provided by the space between the ring 22 and the member 15. In the overflow chamber 24, is an overflow rim 25 for the separating medium, said rim projecting inwardly to a given point determining the amount of the separating medium which may be contained in the chamber 17. In other words, the location of the innermost portion of the rim 25 for all practical purposes determines that the substantially perpendicular surface of the relatively quiescent body of mercury or separating medium in the chamber 17 will be exactly opposite said innermost portion of the rim. It is notable in this connection that the gangue overflow rim 18, projects inwardly to a slightly greater extent than does the rim 25.

The chamber 24 is in communication with the passage 26 established by the space between the wall member 15 and the outer wall proper of the bowl 1, said space leading practically to the bottom of the bowl so as to conduct the separating medium back to the chamber or supply reservoir 13, as said sep-

arating medium moves gradually up over the surface 14, and then outwards over the ring 22 and rim 25.

When the separating medium or mercury reaches the lower end of the passage or space 26, it is conducted by conveyers 27 of the screw type back into the reservoir 13. The conveyers 27 are mounted in tubular members 28, having openings leading downwards to the reservoir 13, and upwards for supplying the separating medium to the surface 14 of the bowl, under the control of valve means to be shortly described. The conveyers 27 are carried by a shaft 29, geared to a shaft 30, connected by bevel pinions with 31, to a stationary shaft 32. The rotation of the bowl carrying with it the shaft 29, in view of the stationary setting of the shaft 32, readily effects the rotation of the shaft 29.

Between the mercury reservoir 13 and the bottom member 12, are disposed valve devices, comprising a circular valve 33, seen best in Figure 3. The valve 33 has openings 34 adapted to register with openings or ports 35 leading through a channel plate 36, suitably screwed to the wall member 15. Obviously, turning of the valve 33 enables registration to a greater or less extent of the openings 34 with the ports 35, and in this way the quantity of the separating medium passing from the chamber 13 upwards to the wall 14 may be regulated.

Any suitable means may be employed to turn or adjust the valve 33, that illustrated comprising a stem 37 mounted in the upper shaft 2 and having a hand wheel 38 at its upper end. The lower end of the stem is connected with the inner fork of an angle lever 39, the outer fork of which, as seen best in Figure 4, engages one arm of a second angle lever 40, the other arm of said angle lever 40 engaging a shift lever 41, pivoted between its ends at 42 and having at its outer end a stud 43 adapted to engage the valve 33. These parts establish an operative connection between the valve 33 and the stem 37. The stem 37 has threaded connection at 44 with the top housing plate 45 of the upper bearing structure 4, so that by turning the stem 37 it may be raised or lowered and movement imparted in this manner to the valve 33 through the intermediate connecting parts just described.

A common method of balancing centrifugal means of the type of this invention is to displace a portion of the metal comprising the centrifugally moving parts as by drilling holes in the heavy side of the rotating body. I employ a unique method of accomplishing the balancing without having recourse to the rather crude method just above referred to. Near the lower portion of the bowl 1, I provide a balancing groove 46 which when empty would, of course, be filled with the separating medium, whatever it may be, in

the course of the operation of the machine. It will be apparent, therefore, that by placing in the groove 46, at the heavy side of the bowl, a segment of light substance such 5 as aluminum, an equal volume of the mobile mass comprising the separating medium will be displaced from the groove. One or more of such segments of light substance may be employed as found necessary and the mere 10 seating of the same in the groove 46 at the proper point or points affords a quick method of placing the machine in proper running balance.

Just above the hopper 11, I provide an 15 oil drip cup 47, for catching the oil that may drip from the bearing structure 4. The overflow rim 25 is retained in place in a seat at the top of the wall proper of the bowl 1 by means of the ring 22. I utilize a rubber 20 bumper 48 as a part of the bearing structure 4, for receiving and absorbing any lateral vibration incident to the high speed action of the rotating bowl 1. The wall member 15 of the bowl 1, is preferably made of a 25 copper alloy for reasons presented more fully in my co-pending application aforesaid.

As to structure, I do not wish to be limited to the precise details of my machine as above disclosed, because they may be modified materially in the practical adaptation 30 of the invention under actual conditions of service.

In the operation of my machine, the pulp supplied to the bowl 1 from the hopper 11, 35 is directed upwards to the mobile wall of mercury or separating medium, owing to the curved form of the bottom member 12. The separating medium passes upwards over the inner surface of the wall member 15, being 40 supplied by the ports 35 under the control of the rotative valve 33. The movement of the separating medium or mercury, over the wall or surface 14, is constant, said medium taking the form of a thin mobile film. As 45 the separating medium reaches a point opposite the annular chamber 17, it unites with the relatively large quiescent body of mercury in said chamber, thereby separating from all material of a specific gravity less 50 than the mercury. The overlying material comprising largely sand and water with the values separated therefrom and received in the pockets 16, floats across the substantially 55 quiescent body of mercury in the chamber 17, and is forced over the overflow rim 19 by the force gained by the said overlying materials as they pass over the curved portion 60 of the ring 22. The overflow rim 18 is of larger diameter than the wall 14 before described, and on this account the overlying materials, primarily sand, moving upward on the inner face of the separating medium are permitted to assume sufficient thickness 65 to pass over the rim 18 without interfering in any way with the upward movement of

the separating medium and residual pulp relatively to the wall 14. The materials pass over the wall 14 at a certain thickness or depth until they reach the curve of the ring 22, whereupon they thin out, so to speak, 70 owing to an increased speed of movement, until they reach the practically perpendicular surface of the mercury in the chamber 17. Not only do the residual materials of the pulp thin out as above described, but 75 this is true respecting the mercury or film of separating medium, the latter being in amalgamated contact with the wall member 15 of the bowl and tending to adhere thereto until it reaches the mercury in the chamber 80 17, whereupon it unites therewith separated from the overlying materials. The rim 18 extends inwardly a very small distance from the face of the mercury in the chamber 17, preventing the latter from escaping over the 85 rim but allowing the sand and water to pass over very readily. The surface of the mercury in the chamber 17 is maintained in proper relation to the inner edge of the rim 18 by the mercury overflow rim 25, which 90 projects inwardly to a point where it maintains the relation aforesaid. The said rim 25 is so located in its innermost portion that the mercury constantly supplied to the substantially quiescent body of mercury in the 95 chamber 17, will pass out of the chamber through the openings 23, over the rim 25, and down the passage 26. Under these conditions, no portion of the separating medium is lost by overflowing over the rim 18. 100

Having thus described my invention what I claim as new is:

1. In a centrifugal separating machine, the combination of a rotating bowl, a reservoir for a separating medium located at the bottom of said bowl, a wall member arranged in the bowl so that its inner surface may be supplied with a separating medium from said reservoir, means for conducting the separating medium from the inner surface 110 of the wall member between the wall member and the bowl and back to the reservoir, means for supplying pulp to the bowl and directing the same over the inner surface of said wall member, and means for regulating the flow of the separating medium from the reservoir to the inner surface of the wall member.

2. In a centrifugal separating machine, the combination of a rotating bowl, a reservoir for a separating medium located at the bottom of said bowl, a wall member arranged in the bowl so that its inner surface may be supplied with a separating medium from said reservoir, means for conducting 120 the separating medium from the inner surface of the wall member between the wall member and the bowl and back to the reservoir, means for supplying pulp to the bowl and directing the same over the inner surface 125 of the wall member.

- face of said wall member, and means for regulating the flow of the separating medium from the reservoir to the inner surface of the wall member, in which the flow regulating means comprises a valve controlling the flow of the separating medium from the reservoir to the inner surface of the wall member.
3. Means substantially as claimed in claim 10 2, in which the flow regulating means comprises a valve controlling the flow of the separating medium from the reservoir, to the inner surface of the wall member.
4. Means substantially as claimed in claim 15 2, combined with a conveyer adapted to move the separating medium from between the wall member and the bowl back to the reservoir.
5. In a centrifugal separating machine, 20 the combination of a bowl and means for rotating the same, said bowl comprising a member equipped with valves receiving pockets, means for supplying a mobile separating medium to the wall member comprising a reservoir for the separating medium, 25 and valve means intermediate said reservoir and a wall member, and means to supply pulp containing values to the bowl.
6. A machine substantially as claimed in 30 claim 5, combined with means to conduct the separating medium back to the reservoir after it has passed over the wall member, and including a conveyer operating incident to the movement of the bowl.
- 35 7. A machine substantially as claimed in claim 5, combined with operating mechanism for the valve means leading to a point exterior to the bowl.
8. A machine substantially as claimed in 40 claim 5, wherein the axis of the bowl is a separating shaft, combined with operating means for the valve means, said operating means being mounted in said shaft and connected with the valve means.
- 45 9. A machine substantially as claimed in claim 5, wherein the axis of the bowl is a separating shaft, combined with operating means for the valve means, said operating means comprising an operating stem mounted 50 in said shaft, and a system of levers connected with said stem, and connected with the valve means.
10. In a centrifugal separating machine, a rotative bowl comprising a wall, means for supplying a separating medium to pass over 55 said wall in the form of a mobile separating film, a chamber at the delivery end of said wall adapted to receive the separating medium after it has passed over the wall, means for supplying pulp to the bowl and directing it against the separating medium so as to flow in the same direction as the latter, and having an outwardly and downwardly inclined under side forming the upper side of said chamber, an overflow rim for the 60 residuum of the pulp after the values have been separated so arranged relatively to the wall aforesaid that the residuum will overflow thereover, a passage communicating with said chamber to receive the separating 65 medium passing into the chamber from the wall, and an overflow rim for said separating medium adapted to maintain the surface of the separating medium in said chamber in such a manner as to prevent passing off 70 of the separating medium with the residuum pulp.
11. In a centrifugal separating machine, a rotative bowl comprising a wall, means for supplying a separating medium to pass over 75 said wall in a form of a mobile separating film, a chamber at the delivery end of said wall adapted to receive the separating medium after it has passed over the wall, means for supplying pulp to the bowl and directing it against the separating medium so as to flow in the same direction as the latter, and an overflow rim for the residuum of the 80 pulp after the values have been separated so arranged relatively to the wall aforesaid that the residuum will overflow thereover, a passage communicating with said chamber to receive therefrom a portion of the separating medium equal to the quantity entering the chamber incident to the movement 85 of the separating medium over the wall, and the second overflow rim intermediate said passage and said chamber, and so arranged relative to the first overflow rim as to prevent the passage of the separating medium 90 off over the latter.
- In testimony whereof I affix my signature.
- RALPH E. LAPHAM.
